UNITED STATES PATENT OFFICE.

MCCLINTOCK YOUNG, OF FREDERICK, MARYLAND, ASSIGNOR TO THE
PALMETTO FIBRE COMPANY, OF ILLINOIS.

GAGE DEVICE FOR BRUSH-MACHINES.

SPECIFICATION forming part of Letters Patent No. 606,871, dated June 28, 1898.

Application filed June 15, 1897. Serial No. 640,888. (No model.)

To all whom it may concern:

Be it known that I, MCCLINTOCK YOUNG, of Frederick, county of Frederick, and State of Maryland, have invented a new and useful Improvement in Gage Devices for Brush-Machines, of which the following is a specification.

This invention has reference to a gage device for use in connection with brush-machines for determining the position of the holes to be bored in the brush-block and for insuring the driving of the tufts in said holes with certainty and precision.

The device is applicable to brush-machines in which the brush-block is supported on a shelf or table beneath the boring or tufting mechanisms, and in certain machines of this description the brush-block is acted upon by a boring-tool, by which holes are made to receive the tufts and is then moved beneath the tufting mechanism in the same machine, by which tufts are driven and secured in the previously-bored holes. In carrying out these operations it is important that the tufts be inserted in the holes with certainty and precision, and to insure this result is the chief aim of my invention, which consists, primarily, in combining with the table or support of the machine a portable brush-block holder, said parts being provided, respectively, with means for securing the holder rigidly in different predetermined positions. These means I embody in the form of a series of sockets in the holder adapted to receive a projection on the supporting-table of the boring mechanism and also a projection on the supporting-table of the tufting mechanism, the relative location, arrangement, and form of the projections and sockets being such that the position of the block with relation to the borer, when a particular hole is seated over the projection beneath the borer, will be the same as its position in relation to the tufting when the same hole is seated over the projection beneath the tufting, and the holder will be prevented from any lateral movement in the plane of the table, but will be permitted to be disengaged from the table in a direction at right angles to the same to change its position from the borer to the tufting. These sockets and pro-

jections may be varied in form and arrangement to accomplish this result. For instance, the sockets may be square or of angular form to receive a projection of corresponding form, or the holder may be formed with two sockets of circular form to receive two projections or pins on the table, which arrangement would permit of the removal of the holder in a direction at right angles to the table, but would prevent the movement of the holder in the direction of the plane of the table.

In the accompanying drawings I have represented my improved gage device in connection with a boring and a tufting mechanism in one machine; but it will be understood that the device may be employed in connection with independent mechanisms for this purpose, provided the projections on the supporting-tables for the two mechanisms occupy such positions in relation to said mechanisms as will insure the same relative positions between the block and the respective mechanisms when the former is changed from one to the other.

In the accompanying drawings, Figure 1 is a perspective view of the supporting-table of a brush-machine and my improved gage device. Fig. 2 is a top plan view of the brush-holder. Fig. 3 is a bottom plan view of the same. Fig. 4 is a bottom plan view of the brush-holder in a different form. Fig. 5 is a perspective view of the supporting-table, having projections to enter sockets of the form represented in Fig. 4. Fig. 6 is a vertical section through a supporting-table in an inclined position and the brush-block holder. Fig. 7 is a longitudinal section through a brush, showing the position of the holes and tufts formed by the use of the inclined supporting-table. Fig. 8 is a transverse section through the same on the line *a a*.

Referring to Figs. 1, 2, and 3, 1 represents a table or support which in brush-machines of the nature referred to is fixed to the frame of the machine in a horizontal position beneath the boring-tool 2 and the tufting 3. 4 represents a brush-block holder consisting of a flat plate which is adapted to rest flatly on the table. This plate has fixed to its upper face,

end, and side supporting-lugs 6, between which the brush-block to be bored or tufted is seated and which is clamped in position by means of a horizontal set-screw 7, mounted 5 in a lug 8 on the plate and having its end arranged to bear against the brush-block. Other means for clamping the block fixedly to the plate may be employed, but I prefer to adopt that shown as being simple and effective.

10 The plate 4 is formed with sockets, consisting, preferably, of a series of holes 9, arranged in two rows, forming radiating pairs situated at intervals around the plate, corresponding to the desired position of the tufts in the 15 brush. These pairs of holes or sockets are adapted to receive projections in the form of two pins arranged side by side beneath the boring-tool and also two pins beneath the tufting-tool, the relation of these two projections to the respective tools being such as to insure the same relative positions of the block to said tools when either pair of the projections extends in the same holes. In boring 20 the holes in the brush-block the plate after being seated on the table, with the two pins entering a pair of holes, is, after a hole in the brush-block is formed, removed at right angles from the table and again seated thereon, with the pins entering the next pair of holes, 25 and a second hole is thus bored in the brush-block. This operation is continued until the desired number of holes is formed in the brush-block. When this operation has been accomplished, the holder, with the brush-block 30 therein, is transferred to the tufting mechanism, and the plate being seated, with the pins entering successively the pairs of holes, the tufts will be inserted in the block in their proper positions with precision.

35 Instead of forming the sockets in the holder by means of two holes to receive two pins on the table the sockets may be of rectangular form, as shown in Fig. 4, to receive a correspondingly-formed lug or projection on the 40 supporting-table, and in both instances the result aimed at will be secured—that is, the prevention of any lateral or side motion of the holder after it has been seated in position to have the brush-block bored or to receive 45 a tuft.

50 When the table is in a horizontal position, as shown in Fig. 1, the holes bored and the tufts seated will be at right angles to the face of the block. In certain forms of brushes, however, the tufts are spread or diverge from the face of the brush-block, as shown in Figs. 55 7 and 8. To accomplish this result, the supporting-table instead of being arranged in a horizontal position is inclined or set obliquely, 60 as shown in Fig. 6, and the spreading or di-

vergence of the tufts will vary according to the degree of the inclination of the table.

The use of my improved gage device in connection with an inclined table for the purpose of setting the tufts, as described, is 65 of peculiar advantage in that each hole will be bored and its tuft set at the proper position and inclination in relation to the plane of the brush, either lateral, as shown in Fig. 8, or longitudinal, as shown in Fig. 7, according to the position of the tuft with relation to the sides or ends of the brush-block.

While I have shown and described the supporting-table as provided with a projection to enter sockets in the holder and while in 75 practice this has been found to answer satisfactorily the ends in view, it will be understood that the invention is not limited to this arrangement, for the same result could be accomplished by forming the sockets in the 80 table to receive a projection on the holder.

Having thus described my invention, what I claim is—

1. In a brush-machine the combination of 85 a table or support and a portable brush-block holder provided respectively with means for securing the holder rigidly in different predetermined positions, substantially as described.

2. In a brush-machine the combination of 90 a table or support and a portable brush-block holder provided with interlocking means substantially as described to retain the holder rigidly in different predetermined positions.

3. The combination with boring and tufting mechanisms, of a work-supporting table therefor, two pairs of pins projecting upwardly from said table and adjacent respectively to said mechanisms, a brush-block 95 holder adapted to rest flatly on the table and provided with two rows of holes forming pairs of sockets side by side, and each pair adapted to receive either of the pairs of pins.

4. In a brush-machine the combination of 100 an inclined table or support and a portable brush-block holder provided respectively with means for securing the holder rigidly in different predetermined positions.

5. The combination with an inclined supporting-table provided with two pins, of a 110 brush-block holder formed with a series of pairs of holes arranged side by side and adapted to receive respectively the two pins.

In testimony whereof I hereunto set my hand, this 9th day of June, 1897, in the presence of two attesting witnesses.

MCCLINTOCK YOUNG.
